UNITED STATES PATENT OFFICE.

FREDERICK L. ROXBROUGH, OF PITTSFIELD, MASSACHUSETTS, ASSIGNOR TO GENERAL ELECTRIC COMPANY, A CORPORATION OF NEW YORK.

SPINNING-FRAME CONTROLLER.

1,358,397.

Specification of Letters Patent. Patented Nov. 9, 1920.

Application filed October 3, 1919. Serial No. 328,213.

To all whom it may concern:

Be it known that I, FREDERICK L. ROXBROUGH, a citizen of the United States, residing at Pittsfield, county of Berkshire, 5 State of Massachusetts, have invented certain new and useful Improvements in Spinning-Frane Controllers, of which the following is a specification.

My invention relates to the control of textile machinery such as spinning frames and the like, and has for its object the provision of an improved means for controlling the speed of the driving motor in accordance with the movement of the ring rail of the 15 spinning machine so as to maintain the tension of the yarn substantially constant. In a prior application for patent to Edwin D. Boles and Emil A. Untersee, filed December 20, 1917, Serial No. 208,102, and assigned 20 to the same assignee of this invention, there is disclosed a form of device for causing the speed of the motor to vary in accordance with the rise and fall of the ring rail. The motor controller is located within the end 25 shield of the motor, thereby making the controller and the motor a self-contained unit connected with the machine only by the driving shaft and by a small shaft which operates the controller. Means are also provided 30 whereby the controlling mechanism may be returned instantly to its initial position at the end of a doff.

My invention is of the same general type of controller and it provides an improved 35 arrangement having features of simplicity, ruggedness, accessibility, and a nicety of adjustment for accomplishing in general the same purposes as devices of the above mentioned application for patent.

40 Other objects and purposes of my invention will appear in the course of the following specification, in which I have shown my invention embodied in concrete form for purposes of illustration.

45 Referring to the drawings, it will be seen that I have illustrated only such parts of the spinning frame as seem essential for the disclosure of my invention, since spinning frames are old and well known and my invention does not depend in any way upon 50 the construction of the spinning machine.

In the accompanying drawings illustrating 55 my invention, Figure 1 is a general view of a portion of the spinning frame, driving motor and controller, and Fig. 2 is a frag-

mentary view of the motor showing my improved controller in the end shield.

Referring to Fig. 1, 10 represents the usual rollers, 11 the wire eye, and 12 the ring rail on which is mounted the ring 13 carrying 60 the traveler 14 of an ordinary ring spinning frame. In order to simplify the drawings as much as possible, I have simply shown the ring rail in a conventional manner as being operated by a lever 15, pivoted at 16. One 65 end of the lever is pivoted to the lower end of the rod 17, the upper end of which is secured to the ring rail so that the ring rail moves up and down with the rod 17. The other end of the lever carries a weight 18 70 for raising the ring rail. The builder mechanism is also illustrated conventionally as consisting of a cam 19 driven through suitable gearing by an electric motor M. The lever 15 is operated so as to raise the weight 75 18 by a flexible cord 20 having one end attached to a segmental arm 21 of the lever 15 while the other end of the cord is attached to one end of the lever 22, pivoted at 23, and adapted to be rotated about its pivot 80 85 by the cam 19. A rod 24, pivoted to the lever 22, extends upward and has in its upper end a roller 25 which engages the face of the cam 19, so that as the cam rotates the rod will be forced downward so as to depress the end of the lever 22 to which the cord 20 is attached. The lever is raised by a weight 26 which holds the roller 25 in engagement with the face of the cam in the upward movement. In order to advance 90 95 the ring rail I have provided means for gradually lengthening the cord. This is done by having the cord mounted upon a shaft 27 driven by a worm wheel 28. This worm wheel is driven by a worm 29 mounted on a shaft 30, to the end of which is secured a ratchet wheel 31. Coöoperating with the ratchet wheel is a fixed pawl 32 so arranged that as the end of the lever carrying the ratchet wheel is raised by the weight 26 the 100 ratchet wheel will be turned by engagement with the pawl 32 so as to rotate the gearing and lengthen the cord. This will gradually lower the weight 18 and advance the ring rail in a well-known manner.

105 As a means for varying the speed of the motor, I have illustrated a speed-varying device of the well-known brush-shifting type, although my invention is not necessarily limited to this particular speed-vary- 110

ing means, since it is also applicable to other well known speed varying elements or devices. As shown the brushes 33 of the motor are attached to a yoke 34 which is adapted to reciprocate back and forth to shift the brushes. This yoke is reciprocated by a mechanism which I shall now describe.

The brush-shifting mechanism or controller receives its motion from the spinning frame 10 by a small shaft which extends through the motor frame. This shaft is driven from the shaft on which the cam 19 is mounted by a sprocket chain 35 and sprocket wheel 36. On this shaft is a cam 37 of substantially the same shape as the cam 19 and is rotated at the same rate as the cam 19.

The operating member for the brush yoke is a pivoted arm 38 which is connected to the brush yoke 34 by a pivotal connection in the form of an adjustable member 39. The connection between the arm 38 and the brush yoke is adjusted by sliding the arm 38 through the pivotally mounted member 39 until the proper position is reached and the arm 38 is secured in that position by the set screw 40. The upper end of the arm 38 is pivotally connected to a lever 41 fulcrumed in a radial slot in one arm of a bell crank lever 42 by the set screw 43. The end of the other arm of the bell crank lever 42 carries a roller 44 adapted to engage the face of the cam 37 so that as the cam rotates it will force the arm 38 downward and consequently shift the brush yoke 34. The arm and brush yoke are returned by the spring 45. By this arrangement the brushes will be shifted back and forth in accordance with the rise and fall of the ring rail. In order to advance the brushes and thus increase the motor speed in accordance with the advance of the ring rail, I provide means for lengthening the effective radius at which the cam lever 42 acts on the arm 38 by varying the position of the connection between the arm 38 and the lever 41. This is accomplished by means of a link 46 pivotally connected to the left hand end of lever 41, and the upper end of which is rotatably mounted on the flat surface of a rotatable ratchet disk 47. The upper end of the link 46 is adapted for radial adjustment with respect to the ratchet disk 47 by means of radial slots. When the upper end of the link 46 has been adjusted to the proper position in the corresponding radial slot, it is secured in that position by means of the set screw 48, the arrangement being such, however, that the upper end of the link 46 is capable of rotation with respect to the surface of the ratchet disk 47. As the ratchet disk 47 rotates, it will carry the link 46 with it and thereby increase the effective radius of the connection between the arm 38 and the lever 43. This disk is gradually rotated by means

of a pawl 49 which rests against the ratchet teeth on the periphery of the disk and is reciprocated as the cam 37 rotates. This is accomplished by mounting the pawl 49 on an arm 50, which in turn is operated by an adjustable eccentric 51, the right hand end of which is connected with and rotated by the cam 37. The pawl 49 is biased into engagement with the ratchet teeth by means of a spring 52. The eccentric 51 is made adjustable by constructing it of two parts, one part having a slot within which a set screw 53 slides, the arrangement being such that the number of ratchet teeth to be picked by the pawl 49 can be predetermined by moving the left hand end of the part 51 with respect to the right hand end to positions indicated by the graduations on the right hand end, when the set screw 53 is tightened and the pawl 49 will continue to pick the number of ratchet teeth thus predetermined. Upon each revolution of the cam 37, the pawl 49 will therefore turn the ratchet disk clockwise determined by the number of teeth picked by the pawl. This ratchet disk 47 is rotated against the tension of a spiral spring 54, one end of which is secured to the disk while the other end is stationary. A pawl 55 holds the ratchet disk in position against the spring tension, and the disk is released so as to permit it to return to its initial position in response to spring tension by lifting the two pawls 55 and 49. This is accomplished by an arm 56 acting on the pawl 55 directly and through the pawl 55, 100 the pawl 49. The arm 56 is operated by means of a rod 57.

From the above it will be seen that as the ring rail rises and falls, the brush yoke 34 will be shifted back and forth to increase 105 and decrease the speed of the motor over a definite range, and at the same time the range is advanced by the rotation of the ratchet disk 47 operating against the spring tension so that when the doff is completed, 110 the controller mechanism will return to its normal position by a similar movement of a handle attached to a rod 57. It will also be seen that the mechanism is so mounted and arranged as to be included in the end shield 115 58 of the motor, there being no connection between the controller within the end shield and the spinning machine other than the shaft on which the gear 36 and a cam 37 are mounted. The motor and controller are, 120 therefore, a self-contained unit which can be easily installed.

The ease with which adjustments may be made and the nicety of the adjustments possible are features of my invention. When 125 the empty bobbin is first started, the speed is set at the minimum. This is necessary on account of ballooning of the thread due to the high speed of the spindle. If the threads balloon too much they touch and 130

break. To set this minimum speed, the set screw 40 is loosened and the brush yoke 34 is moved toward the upper end of the arm 38 until the proper speed is obtained, and 5 the set screw is then locked. The second step is to set the builder speed. As the rail on the spinning frame rises and falls, the speed of the motor changes in time with the rail. The maximum speed is used when 10 the rail is down and the minimum speed with the rail at the top. A variation of from 30 to 100 R. P. M. is used according to the number and kind of yarn being spun. This variation is obtained by the three leafed cam 37 15 moving the bell crank lever 42 which in turn moves the arm 38 and the brush yoke 34. Adjustment of this variation is made by loosening the screw 43 and moving the same toward the center of the cam lever 42 20 for the minimum speed and away from the center for the maximum speed. The third step is to set the maximum speed of the motor which should ordinarily occur when the bobbin is approximately three-fourths full, 25 as the ballooning of the thread at this point is reduced to the minimum. The speed is usually reduced from this point on as the tension on the thread increases until the full bobbin is obtained. The maximum speed is 30 set by moving the ratchet disk 47 in a clockwise direction until the link 46 is over the center of the ratchet disk. The screw 48 is then loosened and the upper end of the link 46 moved toward the center of the ratchet 35 disk until the proper speed is obtained. The fourth step is to set the number of teeth to be picked in order that the ratchet disk will revolve approximately 150 degrees in the same time it takes to fill a bobbin. The 40 screw 53 is loosened and the left hand end of the eccentric 51 is moved until the end comes in line with the proper line indicating the number of picks to be taken. This adjustment regulates the length of stroke for 45 the pawl and in turn the number of picks taken, the object being to have had the ratchet wheel revolve approximately 120 degrees when the bobbin is three-fourths full, at which time the link 46 attached to the 50 ratchet disk is over the center of the ratchet disk. When the disk is revolved the last 30 degrees, the link 46 moves downwardly, lowering the speed and reducing the tension of the thread until the bobbin is full. At this 55 point all the teeth on the disk will have been picked and the disk can revolve no further. This eliminates any chances of breaking the controller. If the same variations in speed are to be used with different yarn 60 but a different range is desired, the set screw 40 is loosened and the brush yoke 34 is adjusted to another position.

In accordance with the provisions of the patent statutes, I have described the principle of operation of my invention together

with the apparatus which I now consider to represent the best embodiment thereof; but I desire to have it understood that the apparatus shown is only illustrative, and that the invention can be carried out by other 70 means.

What I claim as new and desire to secure by Letters Patent of the United States, is:—

1. The combination with a ring spinning machine or the like, of an electric motor for 75 driving the same, means for varying its speed, comprising a speed varying element, a pivoted member reciprocated in accordance with the rise and fall of the ring rail, a lever having its fulcrum on the pivoted member, a link having one end connected to the speed varying element and the other end connected to one end of said lever, and means for moving the other end of said lever to constantly change the radius 80 of action of the point of connection between the link and the one end of the lever so as to shift the range of movement of the speed varying element in accordance with the advance of the ring rail. 85

2. The combination with a ring spinning machine or the like, of an electric motor for 90 driving the same, means for varying its speed, comprising a speed varying element, a pivoted member reciprocated in accordance with the rise and fall of the ring rail, a lever having its fulcrum on the pivoted member, a link having one end connected to the speed varying element and the other end connected to one end of said lever, and means comprising 95 a rotary member connected to the other end of said lever and moved a definite angular distance with each reciprocation of the ring rail, for constantly changing the radius of action of the point of connection between the said link and lever so as to shift the range of movement of the speed varying element in accordance with the advance of the ring rail. 100

3. The combination with a ring spinning 110 machine or the like, of an electric motor for driving the same, means for varying its speed, comprising a speed varying element, a pivoted member reciprocated in accordance with the rise and fall of the ring rail, a lever having its fulcrum on the pivoted member and means for shifting the fulcrum of the lever with respect to the pivoted member, a link having one end connected to the speed varying element and the other end connected to the other end of said lever, and means for moving the other end of said lever to constantly change the radius of action 115 of the point of connection between the link and the one end of said lever so as to shift the range of movement of the speed varying element in accordance with the advance of the ring rail. 120

4. The combination with a ring spinning 125 machine or the like, of an electric motor for 130

driving the same, means for varying its speed, comprising a speed varying element, a pivoted member reciprocated in accordance with the rise and fall of the ring rail,
5 a lever having its fulcrum on the pivoted member, a link having one end connected to the speed varying element and the other end connected to one end of said lever, means comprising a rotary member connected to
10 the other end of said lever for constantly changing the radius of action of the point of connection between the said link and lever so as to shift the range of movement of the speed varying element, means for rotating
15 the said rotary member step by step in accordance with the advance of the ring rail, and means for varying the angular distance the rotary member is rotated at each step.
5. The combination with a ring spinning
20 machine or the like, of an electric motor for driving the same, means for varying its speed, comprising a speed varying element, a pivoted member reciprocated in accordance with the rise and fall of the ring rail, a
25 lever having its fulcrum on the pivoted member, a link having one end connected with the speed varying element and the other end connected to one end of said lever, and means for constantly changing the
30 radius of action of the point of connection between the said link and lever so as to shift the range of movement of the speed varying element in accordance with the advance of the ring rail, comprising a spring
35 return ratchet disk connected to the other

end of said lever, means for rotating the disk step by step against the spring tension, comprising a pawl operated in accordance with the rise and fall of the ring rail, and means for varying the angular distance the 40 ratchet disk is moved at each step.

6. The combination with a ring spinning machine or the like having a bobbin to be filled, of an electric motor for driving the machine, means for varying its speed, comprising a speed varying element, a pivoted member reciprocated in accordance with the rise and fall of the ring rail, a lever having its fulcrum on the pivoted member, a link having one end connected to the speed varying element and the other end connected to one end of said lever, and means comprising a rotary member connected to the other end 45 of said lever and moved a definite angular distance with each reciprocation of the ring rail, for constantly changing the radius of action of the point of connection between the said link and lever to shift the range of movement of the speed varying element 50 in accordance with the advance of the ring rail, and an adjustable connection between the said rotary member and the said other end of said lever whereby the speed of the motor is caused to reach and then recede from a maximum at a predetermined time 55 in the filling of the bobbin.

In witness whereof, I have hereunto set my hand this thirtieth day of September, 1919.

FREDERICK L. ROXBROUGH.
